BUILDING CONSTRUCTION

Guy F. Kotrbaty, New York, N. Y., assignor to
 Ferrocon Corporation, Bryn Mawr, Pa., a corporation of Delaware

Application December 20, 1934, Serial No. 758,346

11 Claims. (Cl. 72—1)

This invention relates to improvements in building constructions and more particularly to basement wall and associated upper wall and floor joints and parts thereof.

5 The building of houses and small buildings of steel members has been appreciably deterred, due to the fact that steel constructions generally have been designed for the use of appreciable amounts of concrete and other structural plastics as structural supporting members and in which the steel is adapted to serve essentially as a skeleton material.

10 A feature of novelty of the present invention is the provision of novel basement wall, building wall and floor joints with supporting and aligning members and structural monolithic building material associated therewith. A further feature of novelty includes the use of starting and aligning structural members adapted to be aligned on a basement wall and to receive and align upper wall and associated floor units.

15 These and other desirable features and advantages of the present invention will be described with respect to the accompanying drawings, certain preferred constructions being shown by way of illustration only, for since the underlying features may be incorporated in other specific building structures, it is not intended to be limited to the one here shown, except as such limitations are clearly imposed by the appended claims. In the drawings like numerals refer to similar parts throughout the several views, of which

20 Fig. 1 is an elevation, partly in broken section, of an improved building showing the method of assembling the novel structural members of the present invention;

25 Fig. 2 is a vertical section of a wall and floor joint taken at basement level;

30 Fig. 3 is an elevation, partly in broken section, of a wall grid supporting member and guide; Figs. 4 and 5 are modifications thereof.

35 Referring now to the drawings, there is shown in Fig. 1 a two story pitched roof dwelling, partly in broken section, to show the improved method of construction. In this drawing the basement and first floor joint is designated generally by the letter A, the second floor and wall joint is designated generally by the letter B, the interior wall and floor joints designated generally by the letter C, and the roof and gable joint is designated generally by the letter D. The several parts can best be considered with respect to the details shown in Figs. 2 to 5, inclusive.

40 In Fig. 2 the joint "A" is formed in the following manner: A cement or concrete footing or

45 abutment 100 is formed in the usual manner, in a trench or in suitable forms. On this footing or support a continuous structural member 200, as shown in Fig. 3, is laid. The member 200 is an elongated member having flanges 201 and 202 at opposite sides of the body portion 203 and respectively extending upwardly and downwardly therefrom. Each of these flanges 201 and 202 is provided with an out-turned stiffening lip designated by the numerals 204 and 205. The body portion 10 203 of the member is provided with a plurality of apertures 206, of the order of 1" in diameter. The upwardly extending flange section 201 is provided with a plurality of apertures 207 of the order of $\frac{5}{8}$ " in diameter. Tongues 202a as shown 15 in Fig. 5, may be used in place of members 202 and bent down to engage the inner edge of the foundation wall.

50 A plurality of structural self-supporting grid members 300 are mounted on the member 200 and abutted against the front panel of flange 201 thereof. The rear flange 202 of member 200 fits against the interior wall of the footing or support 100 when the wall members 300 are in position. Floor members 400 are placed on the supports or 25 guide members 200 and abutted against the wall members 300 or aligning beads 203a, as shown in Figs. 2 and 4. The wall members are provided at their bottom portion with inturned panel portions 301, while the floor members are provided with top panel sections 401 secured to the bottom panels in any desired manner, as by means of a wire tie 402. It will be noted that the members 301 and 401, when bent back, respectively, form a 30 continuous beam-channel section, which is adapted to be filled by a continuous filling 110 of concrete or other suitable class of material. This beam section 110 is continued over the surface of the flooring members 400 to form a concrete surface 111 for the floor members. The concrete 40 of the beam member 110 flows through the apertures 206 of the base guide member uniting with the material of the footing 100 and also flows through the apertures 207 of the front plate, combining with the cement or stucco facing 120 of 45 the outer wall. This stucco or cement facing 120 may be applied on the metal lath panels 302 of the wall members 300, being firmly united thereto and bonded thereby to form a substantially monolithic outer surface supported on a continuous 50 steel frame. The upper panelling 403 of the floor members 400 is embedded in and bonds the cement or concrete flooring 111. The bottom panelling 404, of the floor members 400, is bonded to and serves as an embedment for a plaster coating 125. 55

The panel member 403 may be made of heavy expanded metal lath or perforated steel plates or steel deck material, depending on the load which is to be carried. The non-load-carrying panel 5 member 404 may be made of light gauge expanded sheet metal, which serves as a ceiling support for the plaster coat 125.

A flooring 450 of linoleum or other materials may be laid on the concrete flooring 111, a mastic 10 insert or coating 451 being placed thereunder and adapted to serve as a resilient cement. Corner pieces 452, likewise of linoleum or other suitable material, and preferably so configured and arranged as to provide a rounded corner at the bottom 15 of the baseboard, are fitted at the corners of the room to form water-tight joints which are easily cleaned. In addition, the upper edge of the members 452 is adapted to serve as a plasterer's screed and guide for a finished plaster coat 20 122, which is applied over a scratch coat 121 formed on the inner surface or the inner wall panel 302a of the wall members 300. Where plastic materials generally are to be applied to the several wall and floor members, it is preferred to 25 make the panel sections of the self-supporting grid units formed of expanded metal lath, and usually with horizontal stiffening ribs formed therein.

Reference is made to my companion application Serial No. 758,345, for Structural building elements etc., and filed of even date herewith.

It will now be appreciated that there has been provided an improved building construction in which dwellings and like buildings may be readily made from prefabricated self-supporting wall 35 and floor units, which units, when abutted, are adapted to form composite structural members at the abutting edges. In addition, improved wall and floor joints have been disclosed in which plastic wall surfaces are definitely spaced and 40 separated from each other and in which the main joint members are structurally associated by mechanical means, including associated structural plastic joints, where desired. The wall and floor units may have the desired surfacings or 45 finish formed in place before being assembled to form a complete structure.

While certain novel features of the invention have been disclosed and are pointed out in the annexed claims, it will be understood that various omissions, substitutions and changes may be made by those skilled in the art without departing from the spirit of the invention.

What is claimed is:

1. A joint for building constructions more particularly adapted for basement and wall footing joints, comprising, in combination, a basement wall construction, a structural starting member on the basement wall and including an edge portion adapted to engage the basement wall and be 55 aligned thereby and the other edge forming aligning and receiving means for vertically disposed wall units, vertical wall units and horizontal floor units superposed on the starting member, and a common cementitious bond joining the said basement wall, vertical wall units and floor units.

2. A joint for building constructions more particularly adapted for basement and wall footing joints, comprising, in combination, a basement wall construction, a structural starting member 70 on the basement wall and including an edge portion adapted to engage the basement wall and be aligned thereby and the other edge forming aligning and receiving means for vertically disposed wall units, vertical wall units and horizontal floor units superposed on the starting member in 75

aligned and abutting relationship, and a common cementitious bond joining the said basement wall, vertical wall units and floor units.

3. A joint for building constructions more particularly adapted for basement and wall footing joints comprising in combination a basement wall construction, a structural starting channel on said wall and floor members on said channel, the said wall and floor members comprising self-supporting grids having spaced panels, the inner panel of the wall member and the upper panel of the floor member being respectively folded back from the ends of the grids to form structural plastic receiving channels, structural plastic material in the so formed channels bonding and locking the 15 said wall members and floor members together with the basement supports, the said structural plastic being continued over the floor member to a sufficient depth to form a monolithic surfacing therefor. 20

4. A joint for building constructions more particularly adapted for basement and wall footing joints comprising in combination a basement wall construction, self-aligning apertured wall and floor members on said basement wall, the said wall and floor members comprising self-supporting grids having spaced panels, the inner panel of the wall member and the upper panel of the floor member being respectively folded back from the ends of the grids to form structural plastic 25 receiving channels, structural plastic material in the so-formed channels bonding and locking the said wall members and floor members together with the basement supports, the said structural plastic being continued over the floor member to 30 a sufficient depth to form a monolithic surfacing 35 therefor.

5. A joint for building constructions more particularly adapted for basement and wall footing joints comprising in combination a basement 40 wall construction, a structural starting channel comprising a body portion having a depending rear flange adapted to engage the inner edge of a basement wall, a central longitudinal rib adapted to serve as a guide and alignment for 45 floor grids and an outer upstanding flange adapted to form a wall grid-receiving and aligning channel with the said central rib, the said wall and floor members comprising self-supporting grids having spaced panels, the inner panel of the 50 wall member and the upper panel of the floor member being respectively folded back from the ends of the grids to form structural plastic receiving channels, structural plastic material in the so-formed channels bonding and locking 55 the said wall members and floor members together with the basement supports, the said structural plastic being continued over the floor member to a sufficient depth to form a monolithic surfacing therefor. 60

6. A joint for building constructions more particularly adapted for basement and wall footing joints comprising in combination a basement wall construction, a structural starting channel on said wall and floor members fitted to 65 and aligned by said channel, the said wall and floor members comprising self-supporting grids having spaced panels, the inner panel of the wall member and the upper panel of the floor member being respectively folded back from the 70 ends of the grids to form structural plastic receiving channels, structural plastic material in the so-formed channels bonding and locking the said wall members and floor members together with the basement supports, the said structural 75

plastic being continued over the floor member to a sufficient depth to form a monolithic surfacing therefor.

7. A guide and aligning plate for building constructions comprising an elongated body portion adapted to support and align superposed and abutted wall and floor units, the said body portion having means at one edge thereof adapted to serve as a support and aligning member for wall units and being provided at the other edge with means adapted to be engaged by a basement wall support whereby to align the said plate.

8. An improved guide and aligning plate for structural building constructions comprising in combination an elongated body portion, a central longitudinal rib formed in the body portion, an upstanding flange parallel to the said rib and defining a wall-grid-receiving channel therewith, and a depending flange on the opposite edge of the member from the said upstanding flange forming a guide member for abutment with basement wall constructions, the portion of the plate between the said aligning member and central rib being adapted to serve as a floor grid-supporting and aligning member.

9. An improved guide and aligning plate for structural building constructions comprising in

combination an elongated body portion and central rib being adapted to serve as a floor grid-supporting and aligning member, the said upstanding flange and body portion being severally apertured to permit the flow therethrough of structural plastic materials. 5

10. A structural supporting and guide plate for building constructions comprising a body portion having a front upstanding flange adapted to support and align wall grid members and a rear depending flange portion adapted to be aligned against a basement wall, the said body portion being adapted to support superposed wall grids and floor grids. 10

11. An improved structural member for aligning and supporting juxtaposed wall and floor grid members, consisting of a basement and wall floor joint member comprising a flat body portion having struck out tongues at one side thereof adapted to be bent over and engage a basement wall 20 and an upwardly extending flange at the other edge of the said member, the said flange being adapted to serve as a guide for wall grid members, both the said body portion and flange portion being apertured to permit the flow of structural plastic therethrough. 25
